Patent expires October 7, 1961

3 Claims. (CL 103—129)

1

The present invention relates to control devices for rotary machines such as motors, compressors, pumps and so on, of the kind including two groups of blades or pistons, housed in a cylindrical drum and respectively keyed on independent coaxial shafts turning at variable speeds such that the accelerations of one group correspond to the decelerations of the other group, so as thus to obtain volume variations for the intervals between two adjacent blades, and consequently suction and compression effects in the case of receiving machines or driving effects in the case of motor machines.

The chief object of my invention is to replace the conventional control means for obtaining or transmitting the movement of the blades of pistons, which means included levers, cams, gears, etc., by means which are simpler, stronger and of longer duration, these new means further ensuring a very high power output with respect to the dimensions of the machine.

Preferred embodiments of my invention will be hereinafter described with reference to the accompanying drawings, given merely by way of example, and in which:

Figs. 1 to 3 show, respectively in longitudinal section, in cross section on the line II—II of Fig. 1, and in cross section on the line III—III of Fig. 1, a rotary machine made according to a first embodiment of my invention;

Figs. 4a, 4b and 4c are respective diagrammatical views of a portion of the control device of the machine of Figs. 1 to 3, the parts occupying three different successive characteristic positions; Figs. 5 and 6 show, respectively in longitudinal section and in cross section on the line VI—VI of Fig. 5, a rotary machine made according to a second embodiment of my invention.

The rotary system proper includes as usual, a cylindrical stator or drum 1 in which are fitted two groups of blades 2¹ and 2², each group including four blades at 90° from one another and being mounted on a distinct shaft 3¹ or 3². Shafts 3¹ and 3² are arranged coaxial in the drum and for this purpose blades 2¹ may be keyed on a solid shaft 3¹ which extends over the whole length of stator 1 and blades 2² on a tubular shaft 3² which is freely engaged on shaft 3¹ and which extends substantially over one half of the interval between the lateral walls of said stator. The blades are arranged in such manner as each blade of one group is located between two blades of the other group.

In the wall of the stator 1 I provide holes 4 for the inflow of the fluid (either liquid or gases)

and holes 5 for the outflow of the fluid that is delivered or compressed, these various holes being suitably disposed, account being taken on the one hand of the rotary movement of the blades about the axis of their driving shafts and on the other hand of the relative movement of the blades of one group with respect to those of the other group. Holes 4 and 5 open into inlet conduit 6 or outlet conduit 7 for the fluid, these conduits being for instance provided in the body or frame of the machine.

According to my invention, rotation at variable speed of driving shafts 3¹ and 3² is obtained through two interconnected mechanisms which will be hereinafter described. In the case of the example according to Figs. 1 to 3, these mechanisms are provided on the same side of the drum, which permits of combining together some of the parts, and reducing the space occupied by the whole. In the case of the example according to Figs. 5 and 6, the mechanisms in question are provided on opposite sides of the drum which is better for balancing purposes, more particularly in the case of a motor machine.

In the embodiment according to Figs. 1 to 3, shafts 3¹ and 3² extend beyond the side wall of the drum 1 and to a length such that each shaft end can carry a plate 8¹ or 8² and that an interval is left between said plates for inserting between them a disc 9, driven in a continuous manner and in the desired direction by a main shaft 10 actuated through a pulley such as that designated by 11 on Fig. 5. In the example shown, each of the plates 8¹ and 8² is provided with four radial slideways or grooves 12¹ and 12² respectively, at right angles to one another and plates 8¹ and 8² are so keyed on their respective shafts 3¹ and 3² that their grooves 12¹ and 12² occupy positions, with respect to the corresponding blades 2¹ and 2², such that, when the axes of these grooves are at 45° to each other, the axes of the two groups of blades also make an angle of 45° between them.

On the lateral faces of disc 9 I provide two sets of four fingers or rollers 13¹ and 13², the four rollers of each set being located at the respective ends of two diametral planes at right angles to each other and the two diametral planes of one set being at 45° to the diametral planes of the other set. These sets of rollers are adapted to cooperate with the grooves 12¹ and 12² of plates 8¹ and 8². It follows that continuous rotation of main shaft 10 causes the two groups of blades to rotate at variable speed, and that the engagement of any one of rollers 13¹, for instance in the corresponding groove 12¹ of plate 8¹, when

said plate 8^1 is just for this instant having a speed equal to zero, takes place when one of the rollers 13^2 is at the inner end of its groove 12^2 of plate 8^2 , and, consequently when the speed of plate 8^2 is maximum. All the rollers are at a distance from shaft 10 such that as each of them enters or leaves its corresponding groove, the circular path of travel of this roller is then tangent to the geometrical axis of said groove. This eliminates any cause of shock or noise in the control. A casing 14 surrounds the whole of this control device.

As shown by Figs. 4a to 4c, each inlet hole 4 and a corresponding outlet hole 5 are located close to each other but on opposite sides of a radial plane of drum 1 at right angles to the vertical plane passing through the axes of shafts 3^1 , 3^2 and 10 .

If it is supposed that blades 2^1 and 2^2 respectively cover the corresponding inlet orifice 4 and the outlet orifice 5 (Fig. 4a) and that main shaft 10 is caused to turn, together with rollers $13m$, $13n$ and $13p$ through $22^{\circ} 30'$ in the clock-wise direction (arrow X), I obtain a relative rotation movement in the anticlockwise direction (arrow Y) of blades 2^1 and 2^2 . The interval PON between two adjacent blades, which, in Fig. 4a was about 15° , becomes in Fig. 4b 45° and interval NOM, which was about 75° , decreases to 45° . If the main shaft further rotates to $22^{\circ} 30'$ (Fig. 4c), the interval PON of 45° becomes 75° and the interval of NOM decreases from 45° down to about 15° . Therefore, for a rotation of 45° of the main shaft, the interval between two adjacent blades increases or decreases by 60° . Consequently, for a full revolution of shaft 10 , each interval undergoes four volume increases corresponding each to an angle of 60° , that is to say on the whole 240° and four decreases of volume corresponding also to a total of 240° . As, in the example that is shown, there are eight intervals between the various blades 2^1 and 2^2 , the machine can suck in and deliver a volume represented by $240 \times 8 = 1920^{\circ}$, that is to say $1920^{\circ} : 360^{\circ} = 5.33$ times the useful volume of the cylindrical stator, which corresponds to a particularly high output with respect to the volume and dimensions of the compressor or pump.

In the embodiment according to Figs. 5 and 6, shaft 3^1 extends beyond one of the side walls of the drum 1 and shaft 3^2 beyond the other of these walls, and on each shaft end there is mounted a disc 9^1 or 9^2 carrying a series of rollers 13^1 or 13^2 . These two series of rollers cooperate respectively with plates 8^1 and 8^2 fixed to the main shaft 10 driven by a pulley 11 or the like. The control devices are then housed in distinct casings 14^1 and 14^2 . Despite these differences of construction, the machine according to Figs. 5 and 6 works in a manner analogous to that according to Figs. 1 to 3.

I thus obtain a rotary machine which can be used both as a driving machine, being then fed with steam, compressed air, combustible gases etc., and as a receiving machine (compressor, pump or analogous) for sucking in and discharging liquids or gases, this machine truly complying, in both cases, with the purposes above set forth.

Among the chief advantages obtained by means of a rotary machine of this kind I may state:

1. A high output due to the absence of friction of the movable parts (blades or pistons) against the wall of the stator;
2. An oil consumption practically equal to zero for the same reason;

3. Simplicity and strength of the parts included in the control device and consequently high economy of construction and longer use;

4. A volume occupied about ten times smaller than that of a conventional blade compressor or pump;

5. An excellent volumetric output due to the fact of the low amount of leaks, as these leaks can only take place through leak lines of very small length due to the small dimensions of the machine and for a very short time ($1/8$ of a revolution for the example shown) for the suction and compression strokes.

In a general manner, while I have in the above description, disclosed what I deem to be practical and efficient embodiments of the present invention, it should be well understood that I do not wish to be limited thereto as there might be changes made in the arrangement, disposition and form of the parts without departing from the principle of the present invention as comprehended within the scope of the appended claims.

What I claim is:

1. A rotary fluid machine which comprises, in combination, a frame, a circular drum fixed in said frame and provided with four inlet holes and four outlet holes, every inlet hole and one corresponding outlet hole being disposed on opposite sides respectively of, and adjacent to, one of two diametral planes at right angles to each other, a fluid inlet conduit connected with said four inlet holes, a fluid outlet conduit connected with said four outlet holes, two shafts coaxially journaled in said drum, a set of four blades each at right angles to the adjacent ones fixed to one of said shafts and having their edges adjusted to move along the inner walls of said drum, a set of four blades each at right angles to the adjacent ones fixed to the other of said shafts and having their edges adjusted to move along the inner walls of said drum, said shafts extending to the outside of said drum, two plates fixed to the portions of said shafts on the outside of said drum, each of said plates being provided with four radial slideways located in two diametral planes at right angles to each other, a third shaft journaled in said frame having its axis parallel to that of the two first mentioned shafts and located in the bisector plane of the dihedral angle made by two first mentioned diametral planes, and eight fingers carried by said third shaft adapted to slide respectively in the eight slideways of said two plates, these eight fingers being located in four diametral planes of said third shaft making angles of 45° with one another, all of said fingers being at a distance from the axis of said third shaft such that when a slideway is at an angle of 45° to the above mentioned bisector plane passing through the axis of the three shafts, the corresponding finger is just engaging or leaving said slideway and is moving along a trajectory the tangent to which coincides with the axis of said slideway.

2. A machine according to claim 1 in which the portions of the two first mentioned shafts located on the outside of said drum are on the same side thereof, a plate carried by said third shaft between the planes of the two first mentioned plates carrying the fingers which cooperate with the respective slideways of said two first mentioned plates.

3. A machine according to claim 1 in which the portions of the two first mentioned shafts located

5

on the outside of said drum are on opposite sides thereof.
